UNITED STATES PATENT OFFICE.

FITZ EDWARD PARKLER, OF CHICAGO HEIGHTS, ILLINOIS.

VAGINAL SYRINGE.

Application filed February 21, 1924. Serial No. 694,397.

To all whom it may concern:

Be it known that I, FITZ EDWARD PARKLER, citizen of the United States, residing at Chicago Heights, in the county of Cook and State of Illinois, have invented certain new and useful Improvements in Vaginal Syringes; and I do hereby declare the following to be a full, clear, and exact description of the invention, such as will enable others skilled in the art to which it appertains to make and use the same.

This invention relates to an improvement in syringes, and more particularly, to a vaginal syringe which will be used to thoroughly cleanse the walls of the vagina.

The object of the invention is to provide a suitable construction of syringe which will be formed with a plurality of discharge openings through which a cleansing fluid may be sprayed, to thoroughly cleanse and irrigate the walls of the vagina, and an integrally formed outlet or drain groove whereby the liquid may be removed or drained from the vagina after the same has been cleansed.

The further object of the invention is to provide a vaginal syringe which will be provided with means for discharging a cleansing fluid therethrough, together with means for draining the liquid from the interior of the vagina, and means for regulating the flow of the liquid to and from the syringe, as desired.

Other objects will appear as the description proceeds.

In the accompanying drawings which form a part of my application,

Figure 1 is a side elevation partly in section showing my improvement in vaginal syringes;

Figure 2 is a side elevation of the fluid supply tube and the valved pressure bulb;

Figure 3 is a front elevation of my improvement;

Figure 4 is a side elevation of the regulating means for the fluid;

Figure 5 is a longitudinal sectional view taken on the line 5—5 of the Figure 3; and

Figure 6 is a transverse sectional view taken on the line 6—6 of the Figure 1.

Like characters of reference are used throughout the following specification and the accompanying drawings to designate corresponding parts.

My invention comprises an elongated injection tube 1, which is provided at its for-

ward end with a plurality of radially extending flanges 2, which give a star shaped appearance to the forward end of the said tube. An annular flange or collar 3 is formed adjacent the rear end of the tube 1 and is connected with the downwardly depending outlet or drain groove 4, which extends the full length of said tube.

The injection tube is threaded at its inner end as at 5, and is adapted to support the stopper or shield 6, the inner end of which is spaced a slight distance from the adjacent end of the collar 3, thereby forming an air gap. A hollow nipple 7 is threaded on to the inner end of the tube 1 and serves to hold the stopper 6 in place. The stopper 6 is provided with an outlet or drain passage 8 which is in alignment with the open end of the drain groove 4 and terminates with the extension 9, which is adapted to receive the flexible drain tube 10.

A supply pipe or tube 11 is adapted to be secured to the outer end of the nipple 7, and to conduct the cleansing fluid from a supply receptacle (not shown).

The injection tube 1 is provided at its forward end with a plurality of narrow discharge slots 12, which are positioned between the several radially extending flanges.

The regulating clamp 13 is adapted to be positioned over the tubes 10 and 11 in such a manner that both tubes may be compressed to stop the flow of liquid through the same, or the drain tube may be partially closed prior to the closing of the inlet or supply tube, for purposes hereinafter described. When the clamp 13 is in the position as illustrated in Figure 1 of the drawings, both tubes will be open to freely pass the fluid.

A suitable spring member 14 will be positioned above the supply tube 11 to prevent same from being kinked, and a valved bulb 15 will also be inserted in the supply line 100 so that by squeezing the same pressure may be applied to the fluid as it is discharged from the discharge slots 12 at the outer end of the injection tube.

The operation of the vaginal syringe will now be described: The person desiring to use the syringe lies flat on her back, and the injection tube will be inserted into the mouth of the vagina until the stopper 6 completely seals the same. The inner end 110 of the injection tube will then be directly in front of the mouth of the womb, so that

with the clamp 13 open, the cleansing fluid may freely pass therethrough and be discharged from the slots 12, thereby thoroughly cleansing and irrigating the walls of the 5 vagina and the entrance to the womb. When it is desired to dilate the walls of the vagina, the clamp 13 will be slightly closed to partially close the drain tube 10 which will permit a faster flow of fluid into the 10 interior of the vagina than the outflow of the fluid therefrom. This will cause the fluid to collect within the vagina and consequently dilate the walls thereof so that all of the folds may be thoroughly irrigated.

15 The clamp 13 may then be opened and the fluid will flow through the drain groove 4 and through the outlet passage 8 and drain tube 10 to a waste receptacle.

When the supply of cleansing fluid has 20 been exhausted, there will be a difference of height of the fluid in the drain tube and the supply tube and in view of the pressure of air in the supply tube, there will be a siphoning action which will drain all of the liquid 25 from the interior of the vagina. In most syringes it is practically impossible to use the same while the person is on her back, but with my device it will be quite simple to thoroughly and efficiently manipulate the 30 syringe so that the interior walls of the vagina will be thoroughly cleansed and irrigated, and the fluid which would remain

therein, due to the fact that the mouth of the vagina is on a higher level than the interior thereof, will be positively siphoned 35 therefrom.

If it is desired to secure a greater pressure of the fluid than is possible by having the source of supply elevated above the injection tube, it is made possible by using 40 the valved bulb 15.

It will be understood that while I have described my preferred form of vaginal syringe, I do not intend to limit myself to the specified construction of same, as 45 many minor changes in detail of construction may be resorted to without departure from the spirit of the invention.

Having thus described my invention, what I claim as new and desire to secure by Letters Patent of the United States, is:

In a syringe, a hollow injection tube, a shield mounted upon the said tube, and held in place at one end by a raised shoulder, and at the front end by a threaded nipple, 55 the threaded nipple attached to the end of the said tube, and resting against the concave face of the said shield, the said nipple having at its outer end means for attaching a rubber tube and holding the said tube 60 thereon.

In testimony whereof I affix my signature.

FITZ EDWARD PARKLER.
